MATTHEW J. McNAMARA, OF SCRANTON, PENNSYLVANIA, ASSIGNOR OF ONE-HALF
TO JAMES R. FLEMING, OF SCRANTON, PENNSYLVANIA.

RAILWAY-SWITCH GUARD.

1,426,583.

Specification of Letters Patent. Patented Aug. 22, 1922.

Application filed May 12, 1921. Serial No. 468,892.

To all whom it may concern:

Be it known that I, MATTHEW J. McNAMARA, a citizen of the United States, and a resident of Scranton, in the county of Lackawanna and State of Pennsylvania, have invented certain new and useful Improvements in Railway-Switch Guards, of which the following is a full, clear, and exact description.

10 Among the objects which the present invention has in view are: to reduce the wear on the ends of switch rails; to avoid wearing the extremities of switch rails to a cutting edge; to reduce the shock of impact 15 on switch rails; and to accomplish the above named purposes cheaply and easily.

Drawings.

20 Figure 1 is a plan view of a segment of a railway rail and of the switch rail connected therewith, showing in conjunction therewith a guard plate constructed and arranged in accordance with the present invention;

25 Figure 2 is a cross section of the same, the section being taken as on the line 2—2 in Figure 1.

Description.

30 Heretofore switch rails having wedge-shaped ends such as indicated by the numeral 7 in Figure 1 of the drawings, have been badly worn in service by the flange 8 of a wheel 9, which in service tends to hug 35 the inner side of the head 10 of the railway rails. Hugging the side of the head 10 in the manner referred to, the turning effort of the rail has been borne by the thin edge of the switch rail 7. The grind of repeated 40 wheels has heretofore worn the switch rail and the thin edge thereof to a knife edge, which in a short time impairs the usefulness of the rail. The result of this practice has been that the life of the switch 45 rail has been commensurate with the resistance to the wear of the thin edge of the extremity of the said rail, which necessarily has been, and remains, the weakest portion of the structure.

50 To avoid this wear the present invention provides a guard plate 11. The plate 11 has an upper outwardly curved surface 12,

which is rounded over to approximate the shape of the head 10 of the railway rail. At the ends of the plate rounded or chamfered 55 corners 13 are provided to receive the impact of the flange 8 and thrust the same laterally to separate it from the inner side of the head. When the flange is moved thus, and as shown best in Figure 2 of the 60 drawings, it is held by the straight side of the plate 11, so that when it reaches the same it first contacts with the switch rail 7 at a point approximately that indicated by the numeral 14 or at a point back from 65 the entry edge of the rail. This section of the rail is much better adapted to resist the wear incident to the repeated impact of the wheels in traffic.

The plates 11 are made of suitable material, and are shaped to conform with the head 10 of the railway rail, a recess 15 being formed in the upper end of the plate 11 to conform to the side of the said head. A suitable number of bolt holes are formed 75 in the plate 11 to receive the fastening bolts 16, the heads 17 whereof rest in a channel plate 18, which is shaped to conform to the spact between the flange web and head of the railway rail. Space blocks 19 are introduced 80 between the plate 11 and the web of the railway rail to hold the plate 11 in the desired position with reference to the shape of the rail with which it is associated, and with reference to the desired service 85 position of the plate.

It is obvious that when the plate 11 is in service position in front of switch rails 7, the various wheels of the train as the same approach the switch rail are shifted 90 laterally so that the flange 8 of each of the wheels first strikes the rail 7 at a point removed from the fine edge thereof.

Claims.

1. The combination of a railway rail; a swinging switch rail having a reduced entry end; and a guard member secured in service on the side of the railway rail in advance of the switch rail, said member having an inclined surface for engaging the flange of a railway wheel to shift the same toward the center of a railway track. 95

2. The combination of a railway rail, a

swinging switch rail having a reduced entry end; a guard plate shaped to conform to the side of the rail; and means for removably securing the plate in service position on said rail.

3. The combination of a railway rail; a swinging switch rail having a reduced entry end; a guard plate shaped to conform to

the side of the rail; and means for removably securing the plate in service position 10 on said rail, said means embodying a plurality of bolts, and a spacing block for interposition between said plate and said rail for altering the service disposition of said plate.

MATTHEW J. McNAMARA.
